STABILIZING SYSTEM USING AN
AMPLIDYNE

Edward P. Ney, Minneapolis, Minn., Frank L. Hereford, Jr., Swarthmore, Pa., Walter D. Whitehead, Jr., Old Church, Va., and Alden R. Kuhlthau, Durham, N. H., assignors to the United States of America as represented by the Secretary of the Navy

Application March 4, 1949, Serial No. 79,664

3 Claims. (Cl. 318—142)

1

The present invention relates to a stabilization system which makes use of the amplidyne.

More specifically, it relates to apparatus including an amplidyne whereby devices, such as gun turrets, installed on a rolling or pitching support, a ship, for example, may be kept steady in direction.

The stabilization system consists essentially of a free gyroscope, an amplidyne, a control circuit for the same, a direct current motor and a gear train.

The primary object of the invention is to stabilize a gun director against roll and pitch. An additional object is to provide a device whereby the operator may control the motion of the director by a simple movement of a joystick, instead of manually moving the entire stand, thus relieving the operator of manual labor and allowing him to concentrate his efforts and attention on the more vital features of his work. A further object is to provide means whereby automatic tracking of the target is made possible.

Other objects and many of the attendant advantages of this invention will be appreciated readily as the same becomes understood by reference to the following detailed description, when considered in connection with the accompanying drawing, the single figure of which illustrates the circuits and electrical apparatus involved in a preferred embodiment thereof.

The stabilization signals originate in a gyroscope, not shown, having two pickoff coils 1, which are connected in series-opposition, or "bucking" relationship, to the conductors 2 and 3, which feed the output of said coils to the primary winding 4 of a transformer 5. It will be understood that the pickoff coils are traversed by alternating magnetic flux and are connected to the gyroscope to be moved in their own plane while in said flux, so as to vary the voltages induced therein, as they move to include more or less of said flux.

There is introduced into the circuit a damping signal, here shown as a signal for an induction generator 56 of the "Kollsman" type whose output is connected to the terminals of the resistor 7, which acts as a voltage divider by reason of the movable contact 8, so that any desired portion of the said generator voltage may be put in series with the pickoff coils 1 and winding 4, however, in such direction as to oppose the residual output from the coils 1. This Kollsman generator 56 is driven by the motor 9 which operates the turret to be stabilized.

The output winding 10 of the transformer 5 is

2

center-tapped, as shown, and connected through wires 11, 12 and 13 to the cathodes and grids of a duplex triode, here shown as the tube 14 which may be of type 6N7. A resistor 15 is interposed in lead 12, and may be of the order of 2,000 ohms. The anodes of the tube 14 are connected through wires 16 and 17 to the ends of the center-tapped primary winding 18 of a transformer 26, the said center tap being connected to the positive end of the power supply through the wire 19.

The power supply is relatively simple, and comprises a transformer 21 energized from 110 volt mains, and having the customary secondary windings to supply electricity to tube filaments and heaters, as well as the high voltage energy for the anode circuits. The rectifier 22 suitably may be of the type 5Z3. A choke 29 and a capacitor 23 complete the power supply, which need not be well-filtered, inasmuch as it is not used for the reproduction of sound.

The secondary winding 25 of the transformer 26 is likewise center-tapped. The center tap is connected by a conductor 27 to the cathodes of a pair of tubes 28 and 29, indicated as type 6L6, through the resistor 36, here 1,000 ohms, and transformer winding 31. The outer terminals of the winding 25 are connected through wires 32 and 33 to the control grids of tubes 28 and 29. In one of these wires, for example wire 32, two resistors 35 and 36, each of the order of 5,000 ohms, are connected in series as shown, for a purpose to be described later.

The transformer 31 introduces into the common grid circuit of tubes 28 and 29 an alternating voltage of the order of magnitude of 50 volts. This voltage increases or decreases the voltage applied to the respective grids of tubes 28 and 29 accordingly as the voltage across the secondary winding 25 of the interstage transformer 26 changes phase. This renders the current through the amplidyne fields 41 and 42 a phase-sensitive direct current.

The screen grids of the tubes 28 and 29 are connected by the wire 37 containing three resistors in series, here each of the order of 25,000 ohms. The middle resistor has a slider 34 cooperating therewith as shown and connected by wire 38 to the terminal 39 forming the center tap between two input windings of an amplidyne 40, mechanically driven by the shaft 72 of a constant speed motor 13, and also to the wire 24 which leads to the positive conductor 19 of the power supply. The anodes of tubes 28 and 29 are connected to said terminal 39 through the respective fields 41 and 42 of the amplidyne 40,

by way of terminals 43 and 44 and wires 45 and 46. Each field is shunted by a 0.25 mf. capacitor as shown at 47 and 48.

The amplidyne is a highly specialized form of direct current generator, of the separately excited type. It has two pairs or sets of brushes, set 75 and 76 being in the "normal" commutation plane, the other brushes, 78 and 79, at right angles to said plane, in the electrical sense. The "normal" set of brushes is short circuited by conductor 77, the other delivers the electrical output of the generator, which must of course be driven mechanically.

The characteristic feature of such a generator is that even a small external field will produce strong currents in the short circuited armature windings, thus setting up an intense flux due to the armature reaction. This flux is electrically at right angles to the field flux and is known as "cross flux." It becomes very intense when the brushes are short circuited because of the large currents that then flow in the armature windings.

This cross-field in turn generates relatively great voltages between the brushes constituting the second set, which also constitute the output terminals of the generator. Thus a small change in the field excitation input current causes a large change in the output of the generator. However, if it were attempted to draw current from these brushes, the cross-field thereby generated would in turn oppose and annihilate the normal field. This is prevented by providing a suitably placed compensating field winding, traversed by the entire output current, like the series winding of a compounded generator.

Due to the fact that the amplidyne is separately excited, the output of the machine is not self-sustaining, but is a function of said excitation, and ceases when the latter fails. When driven at a substantially constant speed, the amplidyne thus may be used to provide a relatively great response to a small input current applied to its field winding. The power amplifications secured range from a few hundreds to several tens of thousands, according to the design of the machine.

In the present case, the output of the two 6L6 tubes, 28 and 29, furnishes the variable energization to field windings 41 and 42, and the amplidyne 40 generates, in response thereto, sufficient power to operate the main turret motor 9. It will be understood that the polarity of the voltage generated by the amplidyne depends upon its field polarity and this in turn, through the electronic amplifier system, depends on the direction of shift of the pickoff coils 1, 1.

Thus the gyroscope carrying said pickoff coils controls the operation of the main turret motor 9, as to both the direction and the speed of its rotation. It will be noted that motor 9 is also a separately excited machine, hence reverses its direction of rotation when the voltage applied to the armature changes its polarity.

The output of the amplidyne 40 is connected, through its compensating winding 74, to the motor 9 to operate the latter, and the terminals 80 and 81 of the amplidyne are also connected, by means of conductors 52 and 53, to the corresponding terminals 50 and 51 leading ultimately to the grids of the tube 54. The motor 9, which has its field 57 separately excited, as shown, drives the turret which is to be stabilized and also, through the mechanical connection indicated by the dashed line 55, operates the Kollsman induction generator 56. It will be understood that the line 55 does not necessarily mean a single shaft, but in fact

the Kollsman generator is reduced in speed in the ratio of 1:288 by suitable gearing included in said mechanical connection 55. An alternating current is supplied at low voltage to the input field 5 of the Kollsman generator, and the resulting alternating output delivered from its terminals is fed to the terminals of the resistor 7 one of whose ends is connected to the wire 3, already described. Under the conditions stated, the voltage produced by induction generator 56 will be proportional to the speed of motor 9, and its relative phase will be determined by the direction of rotation of said motor.

Through the wires 52 and 53 the voltage produced by amplidyne 40 is led to the grids of tube 54, through the variable resistor 58 having the adjustable contact 59, and the capacitor 60 in series. A voltage dividing resistor 61 is bridged across the wires 52 and 53 and has an adjustable contact 62 thereon, connected to the cathodes of the tube 54, which preferably is a duplex triode although, of course, two separate triodes could be used if desired.

An independent power supply is provided for tube 54, as an ungrounded circuit is required. This is provided by the transformer 63 energized from the mains, and feeding center-tapped high voltage from a secondary winding to the rectifier tube 64, here a 6X5. The filament or heater may be energized from an appropriate secondary winding on transformer 63 or on transformer 21, as preferred. The smoothing means for the rectified voltage consists of the resistor 65, here 500 ohms, and two capacitors 66 and 67, each suitably being 15 mf. The high voltage direct current output has its negative terminal connected to the cathodes of tube 54 through the wire 68, while the positive terminal is connected to the anode circuit between the resistors 35 and 36, by means of wire 69, which has a variable resistance 71 of the order of 50,000 ohms with the adjustable contact 70, in series therein.

The operation is as follows:

Let it be assumed that pickoff coils 1, 1 are shifted by the gyroscope, out of the neutral position say, into the position illustrated, by reason of tilting of the gun director, due to pitch or roll of the ship. This shift of the coils 1, 1 will cause the lower one to have in an increased voltage induced therein by the A. C. field, whereas the opposing voltage induced in the upper one is correspondingly decreased.

There now is an alternating voltage between conductors 2 and 3, equal to the difference of the two voltages just mentioned, and having a phase relationship or polarity always determined by whichever pickoff coil voltage is the greater. In addition there is also the damping voltage between conductor 3 and the slider 8, which always opposes the voltage differential of the pickoff coils, regardless of its direction. This will be discussed later.

The voltage differential, thus decreased by the damping voltage, is applied to coil 4 of transformer 5, and duly amplified by the electronic tubes 14, 28 and 29 and the circuits associated therewith, with the final result that field 41 or 42 of the amplidyne 40 receives a unidirectional excitation from one or other of tubes 28 and 29, depending upon the relative polarity of the A. C. voltage applied to coil 4, and of a value proportional to said voltage.

This excitation will cause the amplidyne to generate a much increased D. C. voltage of a relative polarity corresponding to that of the orig-

inal differential pickoff signal, and of a relative magnitude likewise corresponding to that of the signal input of coil 4.

Inasmuch as the output of the amplidyne 40, delivered from its terminals 80 and 81, supplies the power to drive the turret motor 9, which is responsive to polarity, said motor 9 will operate in the proper direction to restore the turret to its desired stabilized condition, and at a speed commensurate with the extent of the error from such condition.

The Kollsman damping generator 56 meanwhile is providing a damping voltage proportional to the speed of the turret motor 9, and always of such polarity as to oppose the pickoff differential voltage. This prevents overrunning, as the voltage fed to the motor 9 will begin to decrease before the said motor has finished its proper response, so that the effect of mechanical inertia is thus compensated.

The power supplies, based on tubes 22 and 64 respectively, are or may be conventional and need no further explanation.

The electronic tube 54 and its associated circuit have the purpose of preventing hunting. It will be noted that the grids of this tube are connected to the conductors 52 and 53 which lead to the motor 9. The capacitor 60 in the circuit prevents any current flow through resistors 58 and 61 so long as the D. C. voltage between conductors 52 and 53 remains constant, but permits transient flow whenever said voltage varies. The resultant grid voltage fluctuations will produce corresponding anode current pulses through resistors 35 and 36 which in turn produce varying voltage drops therein, that are fed to the control grid of tube 28.

Due to the tremendous amplification between the pickoff coils 1, 1 and the output of the amplidyne 40, instability would result at the normal zero setting of the pickoff coils, in response to slight parasitic disturbances. Such instability, which would otherwise cause hunting, is offset by the compensating voltage pulses of the control grid of tube 28. Only one of the output tubes need be thus compensated, thus simplifying the circuit.

In order to prevent any disturbance of the normal bias of the said control grid, however, the tube 54 is of the dual type, and the respective anode currents thereof flow in opposite directions through the resistors 35 and 36, to eliminate the voltage drops due to normal anode currents in tube 54. Adjustments are provided by the sliders 59 and 62, the former controlling the sensitivity of the circuit, the latter serving to balance out any inherent differences in the two triodes constituting the tube 54.

It will now be understood that by means of the apparatus described herein, any disturbances of the normally level position of the gun-director support will immediately produce a signal from the free-gyro pickoff coils, which, after amplification, restores the support to its normal position by actuating the turret motor. Usually the whole system is provided in duplicate units, one unit correcting for roll, the other for pitch, but in other respects being substantially identical with one another. Obviously many modifications and variations of the present invention are possible in the light of the above teachings. It is therefore to be understood that within the scope of the appended claims the invention may be practiced otherwise than as specifically described.

What is claimed is:

1. In a damping device for a stabilizing system, comprising, a direct current drive motor, a generator for energizing said motor, a circuit connecting the terminals of said motor and including, in series, a variable resistor, a capacitor and a voltage-dividing resistor having an adjustable contact, a pair of triode sections, said sections having their cathodes connected to each other and to said adjustable contact, and having their respective grids connected to the terminals of said voltage-dividing resistor, a center-tapped resistor having its terminals connected to the respective anodes of said pair of triode sections, a source of electricity having a negative terminal connected to said cathodes and having a positive terminal connected to the center tap of said last-named resistor to supply anode power to said triode sections, and a circuit introducing the voltage between the terminals of said last-named resistor into the field of said generator to control the output of said generator to said motor.
2. In a damping device for a stabilizing system, comprising, a direct current drive motor, an amplidyne generator for energizing such motor, a circuit connecting the terminals of said motor and including, in series, a variable resistor, a capacitor and a voltage-dividing resistor having an adjustable contact, a pair of triode sections, said sections having their cathodes connected to each other and to said adjustable contact, and having their respective grids connected to the terminals of said voltage-dividing resistor, a center-tapped resistor having its terminals connected to the respective anodes of said pair of triode sections, a source of electricity having a negative terminal connected to said cathodes and having a positive terminal connected to the center tap of said last-named resistor to supply anode power to said triode sections, and a circuit introducing the voltage between the terminals of said last-named resistor into the field of said amplidyne generator to control the output of said amplidyne generator to said motor.
3. A stabilization system for a movable element, comprising, a free gyroscope to provide an alternating current signal whenever the element deviates from its desired condition, said signal being phased to correspond to the sense of said deviation, means for providing a voltage opposing said signal, means for amplifying said signal and deriving therefrom a correspondingly polarized unidirectional current, an amplidyne, said amplidyne having its field excited by said current to generate a voltage of a relative polarity corresponding to that of said signal from said pickoff coil and of a magnitude corresponding to the signal input, a direct current motor energized by said amplidyne and operatively mechanically connected with the element to be stabilized, said motor being responsive to polarity so as to be operated in the proper direction to restore the element to its desired stabilized condition at a speed commensurate with the extent of error from such condition, means assisting in preventing hunting of the motor, said means including a circuit connecting the terminals of said motor and having, in series, a variable resistor, a capacitor and a voltage-dividing resistor having an adjustable contact, a pair of triode sections, said sections having their cathodes connected to each other and to said adjustable contact, and having their respective grids connected to the terminals of said voltage-dividing resistor, a center-tapped resistor having

its terminals connected to the respective anodes of said pair of triode sections, a source of electricity having a negative terminal connected to said cathode and having a positive terminal connected to the center tap of said last-mentioned resistor to supply anode power to said triode sections, and a circuit introducing the voltage between the terminals of said last-mentioned resistor into the stabilization system to constitute a component of the control thereof.
